UNITED STATES PATENT OFFICE.

EDGAR H. COTTRELL, OF WESTERLY, RHODE ISLAND.

MACHINE FOR PRODUCING PRINTED PRODUCTS.

1,170,610.

Specification of Letters Patent.

Patented Feb. 8, 1916.

Application filed April 27, 1914. Serial No. 834,662.

To all whom it may concern:

Be it known that I, EDGAR H. COTTRELL, a citizen of the United States, and resident of Westerly, in the county of Washington and State of Rhode Island, have invented a new and useful Machine for Producing Printed Products, of which the following is a specification.

In newspapers and other large printed products of a similar character as now printed and folded parallel with the columns of printed matter, it is well known that because of the very large size of the leaves, the poor quality of the paper used, and the location of the fold, it is extremely difficult to properly handle the paper because of the tendency of the free portions of the leaves above the point held at one side of the paper, to fall over. This tendency is extended to both sides of the paper when the paper is unfolded. Furthermore, it is well known that when the paper is unfolded, it is extremely difficult, awkward and tiresome to properly hold the same for perusal and it is also very difficult to fold back a leaf because of the tendency of a leaf to fall over by gravity in the wrong direction and because of the large size of the sheet.

The object of my invention is to provide a machine which will produce a newspaper which will be very convenient for handling and reading, the newspaper being at all times kept within a reasonable size.

A further object is to provide a machine which will so print the web or webs that the associated sheets cut therefrom may be read from beginning to end by turning the leaves over successively in the same direction.

A further object is to provide a machine in which means are utilized for folding the sheets transversely through the middle of their printed pages or means are utilized for securing the sheets together transversely through the middle of their printed pages or a combination of both of the said means is utilized for folding said sheets together transversely through the middle of their printed pages and securing said sheets together along said fold line.

A still further object of my invention is to provide a machine including mechanisms for so printing the web or webs and so handling the same that each of certain pages

will appear entirely on one sheet and each 55 of other pages will appear partly on one sheet and partly on another sheet.

I have chosen to show, as a practical embodiment of my invention, a machine which will print and deliver a double twelve-page 60 product from two webs.

In the accompanying drawings, Figure 1 represents a diagrammatic elevation of the machine, Figs. 2 and 2^a represent the machine in perspective from the last printing 65 couple of the printing mechanism through to the delivery of the product, Fig. 3 represents a top plan view of a portion of the upper printed web, showing the relative arrangement of the page and page sections 70 thereon, Fig. 4 represents a bottom plan view of a portion of the upper web showing the relative arrangement of the page sections thereon, Fig. 5 represents a top plan view of a portion of the lower web showing the 75 relative arrangement of the page sections thereon, Fig. 6 represents a bottom plan view of a portion of the lower web showing the relative arrangement of the page and page sections thereon, Fig. 7 represents a 80 front view of the printed product in its folded position as delivered from the machine, Fig. 8 represents a front view of the product in its unfolded position, the upper corners of the respective leaves being shown 85 separated to clearly indicate the arrangement of the pages, and Fig. 9 represents a front view of the product after the lower half of the front sheet has been turned over, the lower corners of the remaining sheets being 90 turned over and separated to clearly indicate the arrangement of the pages.

The upper web is denoted by 1 and the lower web by 2. The upper web is led through a perfecting printing mechanism 95 comprising the printing couple 3, 4 for printing on one side of the web, and the printing couple 5, 6, for printing on the other side of the web. The lower web 2 is led through a perfecting printing mechanism comprising the printing couple 7, 8, 100 for printing on one side of the web, and the printing couple 9, 10, for printing on the other side of the web.

The printing mechanisms which act upon the upper and lower webs are so arranged that they will print the front and back pages of the newspaper at different points on

the webs and the intermediate pages each partly at one point and partly at another point on the webs. In the present arrangement, the upper side of one portion of the 5 upper web transversely across the same, will bear page 1, the upper halves of pages 11 and 9, and the lower halves of pages 3 and 5. The lower side of this portion of the upper web will bear, respectively, trans- 10 versely across the web, the upper halves of pages 2, 4 and 6, and the lower halves of pages 12, 10 and 8. The corresponding portion of the upper side of the lower web will bear transversely across the same, respectively, 15 the upper halves of pages 12, 10 and 8, and the lower halves of pages 2, 4 and 6. The under side of the said portion of the lower web will bear, transversely across the same, respectively, the upper halves of pages 3 and 5, the lower halves of pages 11 and 9, and all of page 7.

The webs are here shown as three pages wide and the two webs are brought together as they pass over the roller 11 from whence 25 they pass together through the slitting mechanism 12, 13, where the associated upper and lower webs are slit longitudinally into three pairs of narrow webs. From thence these narrow webs pass over formers 30 14, 15, 16, of the web associating mechanism. From these formers 14, 15, 16, the webs are passed between their respective pairs of rolls 17, 18 and 19, and from thence over the three series of rolls 20, 21, 22, to the pair of rolls 23, 35 where the three pairs of roll webs are associated together. The three pairs of associated narrow webs are then passed through the cutting mechanism 24 where the webs are cut transversely into sheets. These sheets 40 pass through guides 25 to a folding cylinder 26 from which the sheets are folded off by the blades 27 through the rolls 28 to the rotary carrier 29 which deposits the folded product upon the endless delivery carrier 30. 45 The means which I have shown for securing the sheets together transversely across the middle of their printed pages comprises a pasting mechanism 31 arranged to apply paste to one side of the lower web 2 trans- 50 versely along the line between the upper halves of pages 12, 10 and 8, and the lower halves of pages 2, 4 and 6; a pasting mechanism 32 which is arranged to apply paste transversely along the line between the 55 upper half of page 3 and the lower half of page 11 after the pair of wide webs have been separated into the three narrow webs; and the pasting mechanism 33 arranged to apply paste transversely along the line between the 60 upper half of page 9 and the lower half of page 5 after the pair of upper and lower wide webs have been separated into the three narrow webs. This arrangement of the pasting mechanisms will insure the securing 65 of the six sheets together transversely

through the middle of their printed pages without the application of paste to the front or back of the product. If it is desired to secure the sheets together in groups so that each group may be readily separated from the remaining group or groups, it is only necessary to vary the arrangement and number of the pasting mechanisms. The groups of secured sheets may then be folded together as above described. 75

The product produced by my machine will have its front page printed on the front side of one sheet, its back page printed on the back side of the back sheet and the intermediate pages each printed partly on one 80 sheet and partly on another sheet.

To permit the product to be read from beginning to end by turning the leaves over successively in the same direction, the printing mechanism and associating mechanism 85 are arranged so that the printed matter on the front sides of all of the sheets will read in one direction and the printed matter on the back sides of all of the sheets will read in the reverse direction thus causing the last 90 page to be printed in the reverse direction to the first page and the upper half of each intermediate page to be printed in the reverse direction to the first page and the upper half of each intermediate page to be 95 printed in the reverse direction to the lower half of said page.

By the terms "front" page and "back" page, I mean the pages which are located respectively on the front side of the front sheet and the back side of the back sheet of the associated sheets before they are folded together. Similarly, where I refer to the front and back sides of the sheets, I mean before the sheets are folded. 100 105

It is to be understood that any suitable driving mechanism may be used for driving the several parts of the machine so as to insure the proper printing, associating, securing and folding of the product. I have, therefore, not shown such driving mechanism herein as it is well understood in the art. 110

While I have shown an embodiment of my invention which is designed to produce a double twelve-page product from two webs, it is to be understood that I do not wish to limit myself to means for producing a product of any particular number of pages as it is obvious that my invention contemplates means for producing a product of any desired number of pages. Also, while I have shown a product as produced from two webs, it is to be understood that the products contemplated may be produced from one or more webs, as desired. Also, while I have shown means for folding the product transversely across the middle of its printed pages and means for securing the product along said fold line, it is obvious 115 120 125 130

that I may use either one or both of these means as desired without departing from the spirit and scope of my invention.

What I claim is:—

so associate the narrow webs that one page of the newspaper will appear on one sheet, another page on another sheet and the remaining pages will each appear partly on 5 one sheet and partly on another sheet, the printed matter on the front sides of all of the sheets reading in one direction and the printed matter on the back sides of all the sheets reading in the reverse direction, 10 whereby the newspaper may be read from the beginning to end by turning the leaves over successively in the same direction.

8. Means for producing a newspaper comprising a web feeding mechanism, a web 15 printing mechanism, a mechanism for slitting the web into a plurality of narrow webs, a mechanism for securing the webs together, transversely across the middle of the printed pages, a mechanism for associating the webs and a mechanism for cutting the so associated and secured webs 20 transversely into sheets, the said printing and associating mechanisms being so arranged to print the pages on the web and 25 to so associate the narrow webs that one page of the newspaper will appear on one sheet, another page on another sheet, and the remaining pages will each appear partly on one sheet and partly on another sheet, 30 the printed matter on the front sides of all of the sheets reading in one direction and the printed matter on the back sides of all of the sheets reading in the reverse direction, whereby the newspaper may be 35 read from beginning to end by turning the leaves over successively in the same direction, and means for folding the sheets together transversely across the middle of their printed pages.

40 9. Means for producing a newspaper comprising two web printing mechanism, means for feeding webs thereto, a mechanism for associating the two webs, a mechanism for slitting the two webs into a plurality of 45 pairs of narrow webs and a mechanism for cutting the associated pairs of narrow webs transversely into sheets, the said printing and associating mechanisms being arranged to so print the pages on the two original 50 webs and to so associate the said original and narrow webs that one page of the newspaper will appear on one sheet, another page will appear on another sheet and the remaining pages will each appear partly on one sheet and partly on another sheet.

60 10. Means for producing a newspaper comprising two web printing mechanisms, means for feeding webs thereto, a mechanism for associating the two webs, a mechanism for slitting the two webs into a plurality of pairs of narrow webs and a mechanism for cutting the associated pairs of narrow webs transversely into sheets, the said printing and associating mechanisms being 65 arranged to so print the pages on the two

original webs and to so associate the said original and narrow webs that one page of the newspaper will appear on one sheet, another page will appear on another sheet and the remaining pages will each appear partly on one sheet and partly on another sheet, and means for folding the sheets together transversely across the middle of their printed pages.

70 11. Means for producing a newspaper comprising two web printing mechanisms, means for feeding webs thereto, a mechanism for associating the two webs, a mechanism for slitting the two webs into a plurality of pairs of narrow webs, a mechanism for securing the webs together transversely across the middle of the printed pages, and a mechanism for cutting the so associated and secured webs transversely into sheets, the said printing and associating mechanisms being 75 arranged to so print the pages on the two original webs and to so associate said original webs and the narrow webs that one page of the newspaper will appear on one sheet, another page will appear on another sheet 80 and the remaining pages will each appear partly on one sheet and partly on another sheet.

85 12. Means for producing a newspaper comprising two web printing mechanisms, means for feeding webs thereto, a mechanism for associating the two webs, a mechanism for slitting the two webs into a plurality of pairs of narrow webs, a mechanism for securing the webs together transversely across the middle of the printed pages and a mechanism for cutting the so associated and secured webs transversely into sheets, the said printing and associating mechanisms being 90 arranged to so print the pages on the two original webs and to so associate said original webs and the narrow webs that one page of the newspaper will appear on one sheet, another page will appear on another sheet 95 and the remaining pages will each appear partly on one sheet and partly on another sheet.

100 13. Means for producing a newspaper comprising two web printing mechanisms, means for feeding webs thereto, a mechanism for associating the two webs, a mechanism for slitting the two webs into a plurality of pairs of narrow webs and a mechanism for cutting the associated pairs of narrow webs transversely into sheets, the said printing and associating mechanisms being arranged to so print the pages on the two original webs and to so associate the said original 105 and narrow webs that one page of the newspaper will appear on one sheet, another page will appear on another sheet and the remaining pages will each appear partly on one sheet and partly on another sheet, the 110

printed matter on the front sides of all of the sheets reading in one direction and the printed matter on the back sides of all of the sheets reading in the reverse direction, 5 whereby the newspaper may be read from beginning to end by turning the leaves over successively in the same direction.

14. Means for producing a newspaper comprising two web printing mechanisms, 10 means for feeding webs thereto, a mechanism for associating the two webs, a mechanism for slitting the two webs into a plurality of pairs of narrow webs and a mechanism for cutting the associated pairs of narrow webs 15 transversely into sheets, the said printing and associating mechanisms being arranged to so print the pages on the two original webs and to so associate the said original and narrow webs that one page of the newspaper 20 will appear on one sheet, another page will appear on another sheet and the remaining pages will each appear partly on one sheet and partly on another sheet, the printed matter on the front sides of all of the sheets 25 reading in one direction and the printed matter on the back sides of all of the sheets reading in the reverse direction, whereby the newspaper may be read from beginning to end by turning the leaves over successively 30 in the same direction, and means for folding the sheets together transversely across the middle of the printed pages.

15. Means for producing a newspaper comprising two web printing mechanisms, 35 means for feeding webs thereto, a mechanism for associating the two webs, a mechanism for slitting the two webs into a plurality of pairs of narrow webs, a mechanism for securing the webs together trans- 40 versely across the middle of the printed pages, and a mechanism for cutting the so associated and secured webs transversely into sheets, the said printing and associating mechanisms being arranged to so print the 45 pages on the two original webs and to so associate said original webs and the narrow webs that one page of the newspaper will appear on one sheet, another page will appear on another sheet, and the remaining 50 pages will each appear partly on one sheet and partly on another sheet, the printed matter on the front sides of all of the sheets reading in one direction and the printed matter on the back sides of all of the sheets 55 reading in the reverse direction whereby the newspaper may be read from beginning

to end by turning the leaves over successively in the same direction.

16. Means for producing a newspaper comprising two web printing mechanisms, 60 means for feeding webs thereto, a mechanism for associating the two webs, a mechanism for slitting the two webs into a plurality of pairs of narrow webs, a mechanism for securing the webs together trans- 65 versely across the middle of the printed pages, and a mechanism for cutting the so associated and secured webs transversely into sheets, the said printing and associating mechanisms being arranged to so print 70 the pages on the two original webs and to so associate said original webs and the narrow webs that one page of the newspaper will appear on one sheet, another page will appear on another sheet and the remaining 75 pages will each appear partly on one sheet and partly on another sheet, the printed matter on the front sides of all of the sheets reading in one direction and the printed matter on the back sides of all of the sheets 80 reading in the reverse direction, whereby the newspaper may be read from beginning to end by turning the leaves over successively in the same direction, and means for folding the sheets together transversely across 85 the middle of the printed pages.

17. Means for producing a newspaper having separate groups of sheets, comprising means for combining a plurality of printed webs, means for cutting sheets 90 transversely therefrom, and means for securing certain of the webs together in groups transversely through the middle of the printed pages.

18. Means for producing a newspaper 95 having separate groups of sheets, comprising means for combining a plurality of printed webs, means for cutting sheets transversely therefrom, means for securing certain of the webs together in groups trans- 100 versely through the middle of the printed pages, and means for holding the groups of sheets together.

In testimony, that I claim the foregoing as my invention, I have signed my name 105 in presence of two witnesses, this twenty-third day of April, 1914.

EDGAR H. COTTRELL.
